UNITED STATES PATENT OFFICE.

SAM HEDGE, OF DETROIT, MICHIGAN, ASSIGNOR TO HEDGE'S ORANGE ALE COMPANY, OF DETROIT, MICHIGAN, A CORPORATION OF MICHIGAN.

LIQUID-DISPENSING APPARATUS.

1,377,347.

Specification of Letters Patent. Patented May 10, 1921.

Application filed November 13, 1920. Serial No. 423,912.

To all whom it may concern:

Be it known that I, SAM HEDGE, a citizen of the United States, residing at Detroit, in the county of Wayne and State of Michigan, have invented certain new and useful Improvements in Liquid-Dispensing Apparatus, of which the following is a specification.

This invention relates to dispensing apparatus and especially apparatus for dispensing substances that are liquid and preferably carbonated. The idea is to provide a dispensing apparatus that is both sanitary and attractive for display purposes and at the same time has suitable refrigerating means to keep the substance to be dispensed in a properly cooled condition. Furthermore, provision is made for re-charging the container periodically as the substance becomes exhausted. These and other features will appear in the description following.

In the drawings,

Figure 1 is a vertical section of the dispensing apparatus.

Fig. 2 is a cross section on the line 2—2 of Fig. 1.

Fig. 3 is a section taken on the line 3—3 of Fig. 1.

The outer shell is made up of four side walls *a* of German silver joined at their corners preferably by soldering. These side walls have turned-over bottom flanges *b* to which may be soldered or welded the floor *c*. The lower edge portions of the side walls *a* are slightly flared out at *d* for artistic effect. The inner shell or container is made up of a galvanized sheet metal rectangular construction *e* and the bottom *f* forming a box setting in the outer shell which has its turned-out upper edges soldered at *g* to the top plates *h*, which are four in number and secured together at the corners, as shown in Fig. 2. These plates have each a flange or bead *i* that fits over the top of the outer shell *a* and is provided with a turned-in hook *j* that engages over the outside of the outer shell *a*. This inner shell acts as an ice container. The ice may be slipped into the inner shell at the spaces *k* at the corners where the bowl *m* fails to fill out the rectangular opening in the center of the inner container.

The silver-plated bowl *m* is provided with a goose-neck *n* having a flange *o* which may be riveted and soldered to the bottom of the

bowl. This goose-neck has a threaded opening *p* at its lower end adapted to screw over the threads of the nipple *q* which has a flange *r* that is riveted and soldered to the inner container *e*. This nipple *q* extends 60 to the outside of the container and shell where it may be joined by the pipe union *s* with the pipe line *t* that has a valve *u*. This pipe line may connect with any storage tank (not shown) for storing a carbonated 65 liquid.

Whenever the contents of the silver-plated bowl *m* become exhausted or depleted, the valve *u* may be opened, which permits the bowl to again be charged. The 70 goose-neck *n* serves to prevent the solid particles dropping down into the filling tube by gravity. In a great many instances this apparatus will be used with crushed fruit or other forms of fruit, and consequently this 75 fruit might drop down into the feed pipe and cause trouble.

In the chamber *v* between the inner container and the outer shell *a* is the dead air and insulating chamber, which tends to prevent the access of heat to the ice. Supported over the bowl *m* is a glass housing or hood *w* which is secured to the container *e* by bolts *x* that pass through the glass-retaining clips *y*. This hood is provided with only 80 three sides, front and two sides, which are of glass. A rectangular rim *z* rests over the top of the three slabs of glass and is provided with a bead *l* on its inside which forms a support for the glass *2* and forming 85 a tray adapted to carry fruits or other suitable display.

The bowl, as already stated, may be charged with carbonated orange-ade or other fruit juice mixture from a tank (not 90 shown) by simply opening the valve *u*. Within the bowl may be placed crushed, sliced or otherwise prepared fruits which become intermingled with the charged 95 orange-ade or other fluid juice mixture when this is allowed to issue into the bowl in the goose neck *n*. The charging of the bowl with the crushed fruits may be done with a ladle. Access may be had to the bowl through the open rear portion of the glass 100 hood *w* either for charging the same with the crushed fruits or for using the ladle to dip out some of the contents for serving a 105 customer.

It will be apparent that this apparatus 110

provides a neat, sanitary and efficient apparatus for storing and mixing prepared fruits and charged liquids and the same may be placed upon any suitable counter or other support and present an attractive appearance. Furthermore, the top of the hood may be used as a support for fruits to act as a display in advertisement of the liquid being dispensed from the bowl.

10 Obviously other well known refrigerating means could be substituted for ice in the ice container, hence the use of "ice container" in the claims is in the broader significance of a container provided with refrigerating means. Similarly the reference to a hood having an open side in the claims means open when access to the bowl is desired for at other times it might be closed by any removable means and yet such a structure come within the spirit of my invention.

What I claim is:

1. In liquid dispensing apparatus, the combination of an ice container, a bowl supported in the ice container, and a hood supported upon the ice container over the bowl and provided with an open side giving access to the bowl.

2. In liquid dispensing apparatus, the

combination of an ice container, a bowl supported therein, a pipe line leading into the bottom of the bowl for charging the same with a fluid, and a hood supported upon the ice container and open at one side to present access to the bowl.

35

3. In liquid dispensing apparatus, the combination of an ice container, a bowl supported therein, and a hood supported upon the ice container and comprising three transparent sides and an open side to present access to the bowl.

40

4. In liquid dispensing apparatus, the combination of an outer shell, an ice container supported in the outer shell in spaced relation therefrom to leave a dead air space, a bowl supported within the ice container, and a hood supported upon the ice container over the bowl and having one side open to leave access to the bowl.

45

5. In liquid dispensing apparatus, the combination of an ice container, a bowl supported therein, a pipe line leading into the bottom of the bowl and including a goose-neck within the bowl, and a hood supported upon the ice container and open on one side to present access to the bowl.

55

In testimony whereof I affix my signature.

SAM HEDGE.
